MASSAGING DEVICE

Marguerite M. Morrison, Glencoe, Ill.

Application May 19, 1941, Serial No. 394,049

6 Claims. (Cl. 128—57)

This invention relates to improvements in a massaging device, and more specifically to a massaging device highly effective for use in massaging terminal members of the human body, and especially the fingers and toes, although the invention may have other uses and purposes, as will be apparent to one skilled in the art.

I am aware that in the past many and various types of massaging devices have been developed, for use on various parts of the human body, but in so far as I am aware such formerly known devices were not well adapted or desirable for use in massaging terminal members of the body such as fingers and toes. Frequently it is just as desirable, from the standpoint of health and beauty, to massage the hands and fingers as well as other parts of the body, and in the past it has been difficult to adapt or obtain a device for that particular purpose.

With the foregoing in mind, it is an important object of the present invention to provide a massaging device especially designed to massage a terminal member of the body, such as a finger.

Another object of this invention is the provision of a mechanical device designed to aid in the slenderizing and tapering of a finger or toe.

A further object of the invention is the provision of a massaging appliance including a pair of confronting massaging elements carried by resilient means and capable of exerting a yielding pressure upon a finger or the like undergoing treatment, and which may be adjusted by the hands of the user to vary the pressure of the massaging means as may be deemed necessary or desirable.

Still another feature of the invention resides in the provision of a device of the character described wherein a pair of confronting resilient rolls are provided, shaped to accommodate a finger, and carried in frame means sufficiently resilient to permit manual variation of the spacing between the rolls at will, and which permit a separation of the rolls when passing over a knuckle or other region of variation in thickness of a finger, regardless of the manual pressure on the device.

Still a further feature of the invention is the provision of a massaging device for a finger or toe, which device is arranged to automatically compensate for variations in thickness of the part undergoing treatment and thus maintain substantially constant pressure over the entire part.

While some of the more salient features, characteristics and advantages of the present inven-

tion have been above pointed out, others will become apparent from the following disclosures, taken in conjunction with the accompanying drawing, in which:

5 Figure 1 is a fragmentary elevational view of a device embodying principles of this invention, showing the same in use on a finger of one hand of the user while the device is held and manipulated by the other hand of the user;

10 Figure 2 is an enlarged front elevational view of the device of Figure 1;

Figure 3 is a side elevational view of the device of Figures 1 and 2, taken from the opposite side from the showing in Figure 1, or from the right-hand side of the showing in Figure 2; and

15 Figure 4 is an enlarged fragmentary vertical sectional view, with parts in elevation, taken substantially as indicated by the section line IV—IV of Figure 3 looking in the direction of the 20 arrows.

As shown on the drawing:

In Figure 1, the illustrated embodiment of this invention is shown in operative position with the small finger 5 of a left hand 6 undergoing massaging treatment. The device is held between the forefinger 7 and thumb 8 of a right hand 9, the second or longer finger 10 of the right hand also steadyng the device, if so desired. With the hands in the position illustrated in Figure 1, the 30 device may be moved backwards and forwards over the small finger 5, longitudinally of the finger. Obviously, the device may also be placed sidewise, or at any other angle to the vertical, so that the entire finger may be effectively massaged.

35 With reference more particularly to Figure 2, it will be seen that the illustrated form of the invention includes a frame, generally indicated by numeral 11, preferably formed of a piece of metallic ribbon. In the illustrated instance, the 40 end portions of the metallic ribbon have been reversely and inwardly bent to form yoke-like confronting inner frame portions 12—12, and the intermediate part of the ribbon has been shaped to provide an outer and surrounding yoke portion 13. Preferably the only connections between the inner portions 12—12 and the outer part 13 are bend points 14—14, and it will be noted that the bends are somewhat open bends, so that the inner portions 12—12 are substantially equidistantly spaced throughout their 45 length from the outer yoke part 13, and the bend points 14—14 define an opening 15 at one side of the frame for purposes that will later appear.

At one end of the frame the member 13 is provided with a socket 16 in the form of an inward

bend for the reception of the forefinger of the hand, and at the opposite end a similar socket 17 is provided for the reception of the thumb during manipulation of the device. It will be noted that a similar seat or socket 18 is provided at the closed side of the device opposite the opening 15 to accommodate the second or third finger of the hand if the same is deemed necessary to properly hold or guide the device during manipulation. The inner frame members 12-12 are complementary in all portions throughout their lengths to the shape and formation of the outer member 13, and preferably these inner members 12-12 each terminate to one side of the seat or socket 18 in the outer part 13.

The frame 11 carries a pair of spaced rollers 19 and 20, preferably of identical construction. These rollers may be made of rubber, or any other suitable, preferably resilient, material. Each roller is grooved, as indicated at 21, to better contact the finger or toe of the user. Each roller further embodies a metallic shaft or core 22 having reduced opposite ends 23 engaged in suitable apertures in the respective inside frame member 12 so that the roll is freely rotatable.

It is clear from the foregoing description that the rolls 19 and 20 are readily removable and replaceable, if so desired. It is a simple expedient to spring apart the respective inside frame member 12 so as to dislodge an end 23 of a roll shaft and thus remove the roll, a new roll being set in place by a reversal of this process.

The particular frame structure provides a decided advantage in the use of the invention. The construction of the frame is such that it will inherently tend at all times to assume the position seen in Figure 2. That is, the frame is so constructed as to yieldingly resist any tendency to move the rolls 19 and 20 closer together or farther apart. Consequently, the device itself, without any outside aid, is capable of exerting a yielding pressure upon a finger undergoing treatment as illustrated in Figure 1, and the rolls will yieldingly separate when passing over thicker portions of the finger and thereafter contract to assume a firm contact immediately upon reaching a thinner portion of the finger. In addition, the hand holding the device during massaging treatment may press upon the frame 11 and thus vary the pressure of the rolls at will, due to the opening 15 in the side of the frame 11.

It will be especially noted, however, that pressure on the frame element 13 by the hand manipulating the device does not affect the capability of the device to inherently adjust itself to compensate for variations in thickness or conformation of the finger being massaged. While pressure may be applied to the portion 13 of the frame and thereby, indirectly, to the parts 12-12 of the frame, nevertheless the portions 12-12 which carry the rollers 19 and 20 may expand and contract to vary the distance between the rollers in accordance with variations in thickness of the finger being worked upon. This expanding and contracting movement of the inner parts 12-12 of the frame is permitted by the spaces between the parts 12-12 and the outer part 13, and this movement is relative to the outer part 13, which is held in the hand manipulating the device. Thus, there is a cooperation between the frame members so that while pressure of a suitable degree may be applied to the device during use, this pressure being applied directly to the outer frame member 13, such application of pressure does not preclude the inner members 12-12

from permitting a variation in distance between the rolls in keeping with the variation in thickness of the finger undergoing massage treatment, and thus pressure on the finger is maintained substantially constant over the entire finger.

5 It may be noted that when hand pressure is applied to the outer frame part 13 sufficiently to compress the frame somewhat, the rollers may be moved out of parallel arrangement. That is 10 the roller shafts may tend to converge towards the opening 15. This will bring the portions of the rollers nearer the opening 15 closer together than the portions nearer the seat 18. While this will have but a negligible effect on the ordinary massage of a finger or toe, a distinct advantage or use may be made of this feature. Certain fingers, such as a little finger, are most frequently thicker on the inner side than on the outer side, and other fingers may sometimes be thicker on one side than the other. The device 15 may accordingly be positioned to provide more pressure on the thicker side by holding it with the opening 15 to that side, or more even pressure laterally over the finger may be had by holding the device with the seat 18 adjacent the 20 thicker side of the finger, depending on the particular results desired.

As explained above, in use the device is merely moved backward and forward lengthwise of a finger or toe. Thus the device will tend to 25 stimulate circulation, increase suppleness, slenderize and taper the finger or toe, so as to increase the beauty of the individual member and, generally, of the hand or foot.

30 It will be appreciated that while the device is in operation it fits snugly in the hand manipulating the device, seats or sockets being provided in the shaping of the device to accommodate the finger or fingers and thumb of the hand holding 35 it. It will further be noted that while the device itself is capable of exerting a yielding pressure upon the finger or toe undergoing treatment, the device is so constructed as to permit the pressure of the massaging elements to be varied 40 at will, without interference with the movement of the device over varying thicknesses of the finger or toe. It will also be appreciated from the foregoing that the device, while simple in construction and economical to manufacture, 45 nevertheless is highly efficient and easily operated.

50 It will, of course, be understood that various details of construction may be varied through a wide range without departing from the principles of this invention, and it is, therefore not the purpose to limit the patent granted hereon otherwise than necessitated by the scope of the appended claims.

I claim as my invention:

60 1. A finger or toe massaging device, including a frame formed of a ribbon of material bent into generally yoke shape with the end portions reversely and inwardly bent to partially overlap outer portions of the frame and shaped to journal a roller, a massaging roller carried by each 65 of said reversely bent end portions separately from the outer part of the frame, said frame including said reversely bent end portions being bent so as to provide resiliency in the form of 70 a yielding resistance to variation of the distance between said rollers, and said reversely bent end portions being spaced from the outer part of said frame except for the point of connection for each such portion.

75 2. In a digit massaging device, a resilient

frame shaped to provide yoke-shaped end portions with a connection between said end portions on one side only, and a roller journaled in each such end portion, the side opposite said connection being open to permit compression of the frame to bring the rollers closer together with the ends of the rollers adjacent the open side closer than the ends of the rollers adjacent the connection side.

3. In a digit massaging device, a resilient frame shaped to provide confronting yoke-shaped end portions with a connection therebetween at one side only and the opposite side being open between the yoke portions, and a reversely bent portion spaced from and underlying each yoke portion and attached to the respective yoke portion at the open side of the frame only, and a roller journaled in each of said reversely bent portions.

4. In a digit massaging device, a resilient frame including confronting yoke ends movable toward each other against the resiliency of the frame by manual pressure, a cantilever arrangement in each yoke portion and movable rela-

tively to the respective yoke portion, and a roller journaled in each said cantilever arrangement.

5. In a digit massaging device, a resilient frame including confronting yoke ends movable toward each other against the resiliency of the frame by manual pressure, a cantilever arrangement in each yoke portion attached at only one end to said yoke portion and movable both with and relatively to the yoke portion, and a roller journaled in each said cantilever arrangement independently of the respective yoke portion.

6. In a massaging device, a resilient frame including confronting portions movable toward each other by manual pressure against the resiliency of the frame, a reversely bent end portion extending inside and spaced from each of said yoke portions, and a roller journaled in each said end portion independently of the respective yoke portion, said end portions being movable both with and relatively to the respective yoke portions to permit automatic compensation for variances in thickness of that which is massaged.

MARGUERITE M. MORRISON.
